INVENTOR
Joseph E. Papp.

UNITED STATES PATENT OFFICE.

JOSEPH H. POPE, OF HAMILTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON HEELS.

1,346,247.

Specification of Letters Patent. Patented July 13, 1920.

Application filed November 14, 1916. Serial No. 131,832.

To all whom it may concern:

Be it known that I, JOSEPH H. POPE, a citizen of the United States, residing at Hamilton, in the county of Essex and State 5 of Massachusetts, have invented certain Improvements in Machines for Operating on Heels, of which the following description, in connection with the accompanying drawings, is a specification, like reference 10 characters on the drawings indicating like parts in the several figures.

This invention relates to machines for operating on heels and is herein shown as embodied in a machine for attaching heels and 15 top lifts to boots and shoes, although certain of its features may be employed advantageously in machines for pricking or loading or performing other operations upon heels.

20 In machines of this class it is customary to subject the work to a considerable pressure during the operation of the tools and heretofore the machine frame has been constructed sufficiently heavy and thick to

25 withstand the tension developed in the frame during this portion of the cycle. A feature of the present invention consists in an improved frame having its thrust receiving parts connected by tension members which will relieve the frame of tension 30 strains and permit its weight to be substantially reduced. As herein shown tubular tension members are employed and these are advantageously utilized to incase the reciprocatory rods which form a part of the nailing mechanism, and for other functions 35 which will be hereinafter pointed out.

Another feature of the invention consists 40 in a die plate having two die blocks which may be moved alternately from a convenient position for loading at one side of the machine into operative position in line with the driver gang. Advantages of this arrangement are numerous. For example, it 45 enables the operator to confine his attention to operations on the shoe and heel while the assistant supplies the nails, heels and top lifts to that die block which is in inoperative position. It also eliminates the necessity of separate loaders, thus permitting 50 the ends of the drivers to be brought close to the surface of the die plate and the stroke of the machine correspondingly shortened.

Another feature of the invention consists

in novel blank holders so constructed and 55 arranged as to present automatically and accurately position the heel and top lift blanks. The combination of such holders with a movable die plate is believed to be broadly new, as well as certain characteristic 60 features of construction of the holders which will be pointed out hereafter.

Another feature of the invention consists in novel mechanism of simplified and improved form for relatively moving the jack 65 and die plate in applying pressure to the work preliminarily to the operation of the tool gang. As herein shown one pair of cams is utilized to apply both the measuring pressure and the further pressure to the 70 work, one cam being operated in the first operation and the other cam in the second operation.

The present invention also includes among its features novel shoe positioning devices, 75 and novel mechanism for controlling the starting of the machine and the measuring operation.

These and other features of the invention will be best understood and appreciated 80 from the following description of a preferred embodiment thereof selected for purposes of illustration and shown in the accompanying drawings, in which—

Figure 1 is a view of the machine in side 85 elevation;

Fig. 2 is a view of the machine in front elevation;

Fig. 3 is a plan view of the die plate mechanism;

Fig. 4 is a corresponding view in front elevation;

Figs. 5 to 8 are detail views of the breast gage mechanism of the heel and toplift holders;

Fig. 9 is a view in perspective on an enlarged scale of the die plate mechanism shown in Figs. 3 and 4;

Fig. 10 is a plan view of the shoe clamping mechanism;

Fig. 11 is a view in perspective of part of the mechanism shown in Fig. 10, and

Fig. 12 is a plan view of the heel and toplift slide plate.

The machine frame is made in two parts 105 of which the lower part 12 is provided with bearings for the main shaft 16 carrying a loose pulley 18 and a fast pulley 20. The

upper part of the frame 14 is flanged at its lower end and permanently bolted to the bottom part 12. The upper part of the frame 14 is provided with a pair of heavy bosses 15 each bored to permit the passage of a tube 38. The tubes extend through the bottom face of the part 14 where they are threaded and provided with large nuts 40. At its upper end the left hand tube 38 is 10 threaded in a hub 44 which constitutes a part of the die plate section 42. The right hand tube 38 is threaded into a bearing member 50, as shown in Fig. 4, the purpose of which will be presently described. The 15 tubes 38 are preferably formed of steel of high tensile strength and when assembled in the frame part 14 reinforce the latter and provide a composite structure having maximum strength and stiffness for a minimum 20 of weight. The tubes 38 moreover have also the important function of affording casings for the side rods 24 which actuate the nail driving mechanism. Bearings are formed for the side rods in bushings located adjacent to the ends of the tubes 38.

At its forward end the main shaft 16 is provided with a crank 22 which is connected to a lower cross head 26. A pair of side rods 24 extend upwardly from the cross head 26 30 through the tubes 38, being connected at their upper ends with the upper cross head 28. The cross head 28 is provided with a central bore in which is mounted a threaded plunger 30 provided at its lower end with 35 a head 34 having guideways for the reception of the driver block 36 carrying the driver gang. The cross head 28 has an intermediate opening in which is located an adjusting wheel 32 threaded upon the driver 40 plunger 30. By turning the adjusting wheel 32 the vertical position of the drivers and their path of movement may be controlled.

The die plate is made in two sections of which the left hand section 42 is stationary 45 while the right hand section 46 is mounted to revolve about the axis of the right hand side rod upon the stationary bearing member 50. To this end the section 46 of the die plate is provided with a downwardly extending hub 50 48 which rests at its lower end upon ball bearings 49 supported upon an annular shoulder formed in the bearing piece 50, as shown in Fig. 4. At its upper end the bearing piece 50 is threaded to receive a circular 55 nut 47 which, when screwed up to a shoulder on the bearing piece, permits the required movement of the die plate and at the same time holds it firmly against upward movement. The section 46 has secured to its ends 60 the nail blocks 52 and 53 each of which has a curved outwardly projecting flange arranged to fit into a corresponding groove in the die section 42 when the nail block is in operative position. The inner edge of each nail block 65 has a tongue and groove connection with the

section 46 and is detachably held in place by a screw 55 threaded into the section 46 and arranged to enter a tapered hole in the tongue of the nail block, as shown in Fig. 4. When it is desired to fit the machine for a 70 different style of nailing the appropriate nail blocks may be easily substituted in the die section 46 by removing the screws 55.

A heel and toplift holder is arranged beneath each side of the die section 46 being 75 movable longitudinally of the die section to present first the heel and then the toplift beneath the nail block. A flanged guide bracket 60 is bolted to each side of the die section 46, being provided at its lower side 80 with a dovetailed guideway for a slide 62. Each slide carries a heel holder and a toplift holder as shown in Figs. 3 and 12. The heel holder comprises a forked rear gage 64 arranged for adjusting movement longitudinally of the heel and provided for this purpose with teeth which mesh with a worm upon an adjusting screw 66. The toplift holder comprises a similar rear gage 68 mounted for parallel movement in the slide 85 90 and provided with an adjusting screw 70. The breast gage member of the heel holder comprises a bar 72 pivotally mounted on a slide plate 74 having at one side a hub 75 from which extends a rod 76. The rod 76 95 is disposed transversely of the die plate section and provided at its opposite end with a nut 77 against which bears a compression spring 78, as shown in Fig. 8 tending normally to move the rod inwardly and press 100 the gage bar 72 against the heel breast. The rod 76 passes through a threaded opening in a lug on the lower side of the slide 62. An adjusting nut 79 is threaded into the opening by the movement of which the pressure 105 of the gage bar may be adjusted without affecting the position of the bar itself.

In order to permit the adjustment of the gage bar 72 for right and left heels the gage bar is provided with a triangular recess 80 at one side of its axis into which projects a pin 81 on a slide bar 82 which is arranged for movement toward and from the axis of the gage bar. An adjusting screw 84 is threaded in a lug projecting 110 downwardly from the slide plate 74 and provided with a collar which fits loosely in a slot in the under side of the slide bar 82. When the pin 81 is moved into its extreme outer position it is disposed in the apex of 115 the triangular recess 80 in which position it holds the gage bar stationary and in a position at right angles to the longitudinal axis of the heel. When the pin 81 is moved inwardly it permits a graduated amount of 120 lost motion between the sides of the recess so that the gage bar 72 may be swung equally in opposite directions about its pivot, thus affording a symmetrical adjustment for 125 right and left heels. In Fig. 6 the pin 81 130

is shown in position to anchor the breast bar 72 while in Fig. 7 the pin 81 is shown in position to permit the maximum swinging movement of the bar.

5 A gage bar 86 for the toplift holder is provided which is similar in its details to the breast bar 72 of the heel holder above described.

The slide 62 is connected at its inner end 10 to a rod 90 having rack teeth cut in its end portion and being encircled by a compression spring 92 tending normally to move the slide 62 outwardly so as to position the toplift holder beneath the nail block. A pinion 94 on the lower end of a short vertical shaft 96 meshes with the rack 90. The shaft 96 at its upper end is provided with a second pinion 98 arranged to be engaged and rotated by a segmental rack 99 secured to a 15 stationary bracket 54 secured to the upper end of the bearing member 50. The direction of movement of the die plate section 46 is clockwise and in such movement the pinion 94 is turned in the direction to move 20 the slide 62 toward the right as seen in Fig. 3 compressing the spring 92 and bringing the heel holder beneath the nail block 52 which, at the termination of this movement, occupies the position of the nail block 53, as 25 shown in Fig. 9. The slide 62 is provided in its upper surface with a recess for the locking pin 100 which is arranged to be automatically released by a downward movement 30 of the cross head in the heel attaching operation. For this purpose an adjustable trip rod 103, shown in Fig. 1, is mounted at the rear side of the cross head and arranged to engage the trip lever 102 as above indicated. It will be understood that the locking pin holds the slide 62 with the spring 35 92 under compression and that the action of this spring is effective to shift the heel and toplift holders. The rod 90 carries at one end an adjustable stop 104 which engages a normally stationary but yielding 40 stop 106 on the plate 60 when the slide 62 is tripped, thus determining the position of the slide when the top lift holder is to occupy its proper position beneath the nail block. It will be understood that similar 45 mechanism is provided at each end of the die plate section 46 so that whenever either nail block occupies its outermost position, as does the nail block 53 in Fig. 2, the heel holder will be positioned in readiness to 50 receive a heel blank.

The stationary tubes 38 have also the function of guideways for the jack carriage 110 which is provided with semicylindrical 55 slides 112 shaped to fit the inner surfaces of the tubes 38. The jack carriage includes a transverse shaft 113 upon which is pivotally mounted a bracket 114 which carries the jack parts. The jack heel post 116 projects 60 upwardly from the bracket 114. This will

not be herein specifically described as it is fully disclosed in United States Patent No. 1,313,909, granted Aug. 26, 1919, on an application filed by me. The toe post 118 is pivotally mounted in the bracket 114 and 65 provided with a slotted arm 120 through which passes a pin 121 in the bracket. The pin and slot connection permits limited swinging movement from front to rear of the toe post 118 while the thumb nut 122 70 is provided for clamping the toe post in the desired position.

The toe post 118 is provided with a hinged joint at its lower end, as shown in Figs. 1 75 and 2, permitting the post to swing for a right and left adjustment. Above the hinge the post is threaded and provided with an adjustable collar 123. When the collar is screwed down tightly against the lower part of the hinge the post 118 is held in a 80 central position. As the collar 123 is adjusted upwardly upon the post an equal swinging movement to the right or left is permitted.

The jack carriage 110 is moved vertically 85 with the shoe first to measure the work and then to apply pressure thereto. The mechanism for effecting the measuring operation will now be described. A swinging cam piece 124 is mounted for movement about the transverse shaft of the jack carriage and provided at its lower surface with a hardened cam 126. Normally the cam 126 rests upon a roller 128 extending across between the inner ends of a forked lever 130 90 pivotally mounted on a bracket 132 bolted to the frame part 14. The cam piece 124 is provided with a rearwardly extending arm to which are connected the upper ends of a pair of rods 150 extending downwardly to 95 the treadle levers 152. The rods 150 are bent as shown in Fig. 2 and provided with a spreader 154 against the under surface of which bear the compression springs 156 which serve to hold the treadle levers in elevated position and also to maintain the cam piece 124 in its initial position as shown in Fig. 1. When the treadle levers 152 are depressed by the operator the cam piece 124 is rotated in a counter-clockwise direction 100 and the jack carriage is moved until this movement is arrested by engagement with the desired degree of measuring pressure of the shoe and heel to be attached. The jack carriage is given its further upward movement to apply pressure to the work by mechanism which will now be described. A bell crank pressure lever 136 is journaled in the frame 14 and arranged to engage at its short end against the surface of the cam 126. At 105 its rear end the presser lever 136 is connected through a pair of links to a crank rod 138 operated by a pair of cranks 140 on the main shaft 16. By referring to Fig. 1 it will be seen that when the shaft 16 is turned to 110

lower the rear end of the presser lever 136 the jack carriage will be given a further upward movement of predetermined amount, this movement occurring independently of 5 and in addition to the upward movement which has taken place in the measuring operation.

In order to regulate the amount of movement imparted to the jack carriage in applying 10 the final pressure, provision is made for preliminarily adjusting the position of the roller 128. For this purpose the outer end of the forked lever 130 is connected to a stationary pin 131 on the bracket 132 by 15 means of a threaded expansible connection and an adjusting wheel 129 is provided for regulating the length of this connection. Thus, when it is desired to reduce the 20 amount of the final pressure movement, the adjusting wheel 129 is turned in a direction to elevate the pin 128 and the jack carriage supported thereby. The effect of this 25 adjustment is that the initial movement of the presser lever 136 becomes lost motion and the jack carriage is elevated only during the latter part of this movement. On the other hand, by lowering the pin 128 the full movement 30 of the presser lever 136 is made effective and the pressure applying movement of the jack carriage is correspondingly increased.

It is important that the nail block 52 or 35 53 should be accurately located in operative position before starting the machine as otherwise the drivers would not properly enter the driver passages in the nail block. To this end the die plate section 46 is provided in its lower surface with a pair of recesses adapted to receive the upper end of 40 a vertical rod 160 connected at its lower end to the forwardly extending arm of a bell crank lever 162 journaled in the machine frame. The upwardly extending arm of the lever 162 is arranged to stand beneath a projection 45 on the cam piece 124 whenever the rod 160 is depressed as it is unless seated in one of the two recesses in the die section 46. Under these circumstances the cam piece 124 is locked against movement and the operator 50 is unable to effect the measuring operation until the die section has been moved into its proper operative position.

Each of the locking recesses is provided with an inclined approaching surface so that 55 when the die section 46 is rotated the end of the rod 160 will be forced downwardly, swinging the upper end of the lever 162 forwardly. It will be apparent that this cannot occur as long as the projection on the cam piece 124 is in front of the lever 162 and, consequently, the die block is locked in 60 operative position as long as the jack is in operative position or, in other words, until the treadle is released and the rod 150 allowed to rise.

It will be noted that the jack is arranged to swing forwardly to receive the shoe and then rearwardly into operative position beneath the nail block. Mechanism for locating and clamping the counter portion of the 70 shoe in the proper position beneath the nail block is shown in Fig. 10. A flexible counter clamp 170 is connected at either side through a link 172 to the inner end of a threaded rod 174 upon which is journaled a 75 sprocket wheel 176. The rod 174 slides longitudinally in bearings formed in a piece 177 bolted to the forwardly extending arms of a yoke-shaped bracket 178. The outer surfaces of the pieces 177 are planed 80 and arranged to slide upon corresponding surfaces formed in the machine frame. By turning the sprocket wheels 176 in the proper direction the opening of the counter clamp 170 may be increased or reduced. 85 Means are provided for independently or jointly effecting adjustment of the sides of the clamp. To this end a pair of aligned shafts 180 and 182 are journaled in the rear part of the bracket 178 and are each provided with a sprocket wheel 181 over which runs a chain connecting the shafts 180, 182 with the sprocket wheels 176. The shafts 180, 182 are normally connected by a toothed clutch 184. The shaft 180 is movable longitudinally and normally held in position to engage 90 the clutch 184 by a compression spring 185. A knurled nut 183 is provided on the outer end of each shaft for convenience in turning the same. When the clutch 184 is engaged, 100 rotation of either nut turns both shafts and effects an equal and opposite adjustment of the band clamp. If it is desired to effect an individual adjustment the shaft 180 is moved toward the right, as seen in Fig. 10, and may 105 be turned while so held to adjust the right side of the clamp while at the same time the shaft 182 is freed so that the left side of the clamp may be adjusted.

The bracket 178 is supported by a carriage 110 115 arranged for vertical movement in the machine frame with the jack carriage 110 and also for independent vertical adjusting movement. The jack carriage is provided with a rearwardly extending plate 192 having a threaded hub in which is mounted a right and left screw 194 having a hand wheel 196. At its upper end the screw 194 enters the threaded hub of the carriage 190 and it will be seen that rotation of the wheel 196 120 adjusts the carriage vertically with respect to the plate 192 of the jack carriage. The bracket 178 is also arranged for horizontal adjusting movement upon the carriage 190. To this end the carriage is provided with a 125 horizontal guiding surface for the bracket 178 and with a pair of vertical bolts which extend through parallel slots in the bracket. A threaded adjusting rod 198 projects from the rear side of the bracket through a lug on 130

the carriage 190 and an adjusting wheel 199 is provided for turning the rod to shift the bracket forwardly or rearwardly.

The band clamp 170 is arranged for angular adjusting movement about the axis of the pins 174 and to this end is provided with a rearwardly extending rod 200 which projects into a curved slide piece 202. The slide piece is arranged for movement in 10 curved dovetailed ways 203 formed in a portion of the bracket 178, as shown in Figs. 10 and 11.

The treadle mechanism comprises a pair of treadle levers 152 pivoted at the rear portion 15 of the frame 12, and connected by a cross rod 209 upon which are journaled a pair of yoke-shaped frames 211. The ends of the rods 150 pass into the yokes 211 to which they are connected through springs 213. 20 This construction permits depression of the treadle levers 152 after the downward movement of the rods 150 has been arrested at the completion of the measuring operation. This lost motion may or may not be required 25 in order to trip the main clutch, as will presently appear. Each treadle lever 152 carries a pivoted arm 216 between the forward ends of which extends the treadle plate 210. A spring 215, shown in Fig. 1, holds 30 the treadle plate 210 in one of two positions; viz., an operative position, as shown in full lines in Fig. 1 where the inner ends of the arms engage lugs upon the treadle levers 152, or in an inoperative position in which 35 the arms 216 extend vertically into engagement with the base of the frame. The arms are moved into the latter position by the operator when he desires to lock the treadle against depression.

40 The clutch is tripped by swinging forwardly the arm 222 pivotally mounted upon the base of the frame and having a forwardly extending arm 220. For this purpose each treadle rod is provided with a 45 hinged trip piece 218 having a downwardly extending arm arranged to encounter the horizontal arm 220 and depress the latter when the treadle is operated. Continued downward movement of the treadle carries 50 the arm of the tripping piece 218 out of engagement with the arm 220 and prevents the clutch from being again tripped until the treadle levers have been permitted to resume their normal elevated position. The 55 treadle plate 210 is provided with an aperture through which extends the end of an auxiliary treadle 212 which is connected to a stop member 214. Normally the operator will disregard the auxiliary treadle 212 but 60 in case it should be desired to depress the treadle sufficiently to measure the work, and at the same time insure that the main clutch shall not be tripped, the operator will depress the treadle plate 210 at the point 65 where the auxiliary treadle 212 appears.

Under these circumstances the stop 214 will be swung downwardly and will encounter the base of the frame and so arrest the treadle levers 152, preventing the latter from being moved sufficiently to trip the 70 clutch.

The operation of the machine will be apparent from the foregoing description but may be briefly outlined as follows: With the machine in the condition shown in Figs. 75 1 and 2, the operator will pull the jack forwardly to place upon it a shoe to be heeled while at the same time nails will be supplied to the outermost nail block and the heel blank and toplift will be inserted in 80 the respective holders. The die section 46 is then rotated, carrying the loaded die block into position beneath the drivers with the heel blank in operative position. The jack is then pushed rearwardly and the 85 counter portion of the shoe accurately located by the band clamp 170. The operator now depresses the treadle plate 210 first swinging the cam piece 124 to effect the measuring operation and then tripping the 90 main clutch whereupon the final upward movement is imparted to the jack carriage and the cross head is moved downwardly to drive the attaching nails. In the downward movement of the cross head the heel and 95 toplift holder is tripped and during the upward movement of the cross head the holder is moved from right to left to properly position the toplift. The operations above described are now substantially 100 repeated in order to spank the toplift upon the attached heel and subsequently the die plate section 46 is given a half revolution to bring the machine parts into initial position in readiness for a new cycle. 105

Having thus described my invention, I claim as new and desire to secure by Letters Patent of the United States:

1. A machine for attaching heels, having, in combination, a nailing die movable between nail loading and heel attaching positions, heel and top lift holders associated with the die and constructed and arranged to position alternatively a heel or a top lift in register with the die, and means for 110 automatically moving said holders alternately into register with the die in proper time relation to the movements of the latter. 115

2. A machine for operating on heels having, in combination, a circularly movable 120 nailing die, a reciprocating gang of tools, heel and top lift holders movable radially of the die, and means controlled by the reciprocation of the tools for effecting radial movement of said holders to substitute one 125 for the other.

3. A machine for operating on heels, having, in combination, a frame having a die plate and shoe support relatively movable to subject the work to pressure, a tubular 130

- 10 tension member connected to either end of the die plate, operating rods arranged to reciprocate within the tubular members, and a gang of tools carried thereby.
- 15 4. A machine for operating on heels, having, in combination, a frame including parallel tubular tension members, reciprocatory side rods of greater length than the tubular members arranged to reciprocate therein and connected at their ends by cross heads, and a gang of tools carried by one of the cross heads.
- 20 5. A machine for operating on heels, having, in combination, a frame having a die plate, a thrust receiving part spaced from the die plate, a shoe support, mechanism re-acting against the thrust receiving part for moving the shoe support toward the die plate, tubular tension members connecting the die plate and said thrust receiving part, and nailing mechanism including side rods arranged to reciprocate in the tubular members.
- 25 6. A machine for operating on heels, having, in combination, a frame part provided with bearings for a shaft having operating cranks, and a second frame part detachably secured to the first and carrying nailing mechanism and relatively movable members for applying pressure to the work, together with operating trains of mechanism between the operating cranks on the one hand and the nailing mechanism and one of the pressure applying members on the other hand.
- 30 7. A machine for operating on heels, having, in combination, a frame having a pair of parallel tubes, a jack carriage disposed between the tubes and shaped to be guided thereby, operating rods arranged to reciprocate in the tubes, and a gang of tools operated thereby.
- 35 8. A machine for attaching heels, having, in combination, a pair of die blocks, a supporting member for the die blocks rotatable to present them successively in nail loading and heel attaching positions, a gang of tools, and stationary means for supporting at its outer side each die block brought into line with the tools.
- 40 9. A machine for operating on heels, having, in combination, oppositely disposed thrust receiving members connected by tension members, and means for subjecting a heel and shoe to pressure between the thrust receiving members, one of said members including a stationary section and an interlocking pivotally mounted section having a plurality of die blocks movable alternately into thrust receiving position.
- 45 10. A machine for operating on heels, having, in combination, a frame having a movable jack, and an oppositely disposed abutment comprising a grooved stationary member, and a rotatable carrier having a plurality of separable die blocks tongued to fit the groove in the stationary member.
- 50 11. A machine for operating on heels, having, in combination, a frame having a movable jack, an oppositely disposed abutment including a die carrier rotatable independently of the movement of the jack, and means responsive to the movement of the jack for locking the die carrier in operative position.
- 55 12. A machine for operating on heels, having, in combination, a frame, a jack movable therein, an abutment including a die block movable to and from a position in alignment with the jack, and means for moving the jack to measure the work and simultaneously lock the movable die block in position.
- 60 13. A machine for operating on heels, having, in combination, a vertically movable jack, an abutment including a horizontally movable die block, means for moving the jack to measure the work, and locking mechanism constructed and arranged to prevent operation of said means when the die block is not properly positioned and to lock the die block in position when the jack is moved.
- 65 14. A machine for attaching heels, having, in combination, a pivotally mounted carrier having a pair of die blocks arranged to be presented alternately in nail loading and attaching positions, and heel and top lift holders associated with each die block.
- 70 15. A machine for operating on heels, having, in combination, a carrier mounted for pivotal movement, die blocks 52 and 53 on the carrier, a heel holder and a top lift holder associated with each die block, and means for moving the holders alternately into operative position with relation each to its associated die block in proper time relation to the movements of the latter.
- 75 16. A machine for operating on heels, having, in combination, a carrier mounted for turning movement, a die block mounted at each of the outer ends of the carrier, heel and top lift holders associated with each die block and movable radially with respect to the carrier, and means controlled by movement of the carrier for effecting such radial movement.
- 80 17. A machine for operating on heels, having, in combination, a pair of die blocks mounted for turning movement about an intermediate axis, heel and top lift holders associated with each die block, and means for automatically positioning one of said holders in operative relation to its associated die block when the latter is swung into inoperative position in the machine.
- 85 18. A machine for operating on heels, having, in combination, a pair of die blocks mounted for turning movement about a com-

- inon axis, heel and top lift holders arranged to be locked with one holder initially in operative position, means for locking the holders in said position, and separate means for 5 substituting one holder for the other.
19. A machine for operating on heels, having, in combination, a die block mounted for turning movement about an external axis, heel and top lift holders associated there- 10 with, and means for bringing the heel holder automatically into operative relation to the die block by the turning movement of the latter out of its operative position in the machine.
20. A machine for operating on heels, having, in combination, a die block mounted for turning movement about an external axis, a blank holder associated with the die block, and mechanism for moving the blank holder 15 relatively to the die block when the die block is turned, said mechanism being constructed and arranged to release the holder after having moved it to a predetermined point.
21. A machine for operating on heels, having, in combination, a die block mounted to move about an external axis, a blank holder associated with the die block, spring operated actuating mechanism for moving the 20 holder relatively to the die block arranged to be energized when the die block is turned, and means for automatically rendering operative said mechanism when the blank has been operated upon.
22. A machine for operating on heels, having, in combination, a pivotally mounted carrier having a die block at either end, a heel and top lift holder associated with each die block, and means for moving each holder 25 radially in one direction while the carrier remains at rest and in the opposite direction when the carrier is turned about its pivot.
23. A machine for operating on heels, having, in combination, a pivotally mounted 30 carrier having a die block mounted therein, a blank holder slidable upon the carrier, rack and pinion mechanism for moving the holder in one direction when the carrier is turned arranged to become disengaged when the holder has been so moved, a latch for 35 maintaining the holder in position, and yielding means for moving the holder when the latch is released.
24. A machine for operating on heels, having, in combination, a carrier having a die 40 block, a segmental gear disposed adjacent thereto, a blank holder slidable on the carrier, and operating mechanism including a pinion arranged to coöperate with the seg- 45 mental gear, said carrier and gear being relatively movable to shift the position of the holder relatively to the carrier.
25. A machine for operating on heels, having, in combination, shoe supporting means, and a blank holder including a pivoted 50 breast bar having a triangular recess, and a stop pin adjustable toward and from the apex of said recess.
26. A machine for operating on heels, having, in combination, a jack and die plate ar- 55 ranged for relative movement, a starting treadle constructed and arranged for moving one of said elements to measure the work, and an auxiliary treadle for limiting the movement of the starting treadle. 60
27. A machine for operating on heels, having, in combination, work pressing and nail driving mechanism, a starting treadle arranged to control the work pressing mechanism and having a foot plate extending 65 across the front of the machine with an aperture therein, and an auxiliary treadle disposed within the aperture for limiting the movement of the starting treadle.
- In testimony whereof I have signed my 70 name to this specification.

JOSEPH H. POPE.
